UNITED STATES PATENT OFFICE.

JOHN C. SPEIRS, OF WORCESTER, MASSACHUSETTS, ASSIGNOR TO THE LOCOMOBILE COMPANY OF AMERICA, OF NEW YORK, N. Y.

DESIGN FOR A TOP PLATE FOR HYDROCARBON-BURNERS.

SPECIFICATION forming part of Design No. 33,737, dated December 18, 1900.

Application filed November 23, 1900. Serial No. 37,547. Term of patent 14 years.

To all whom it may concern:

Be it known that I, JOHN C. SPEIRS, of Worcester, in the county of Worcester and State of Massachusetts, have invented and produced a new and original Design for a Top Plate for Hydrocarbon-Burners, of which the following is a specification.

This invention consists in a novel design for the top plate or sheet of a hydrocarbon-burner, the same being illustrated in the accompanying drawings, in which—

Figure 1 represents a top plan view of a burner-plate embodying my design. Fig. 2 represents a median section thereof on the line 2 2 of Fig. 1.

The distinguishing features of my design are as follows: 1 is a laterally-extensive rela-

tively thin plate or sheet pierced by numerous holes 2 2, spread out over the plate, and the several holes being surrounded each with 20 an annular bead or ridge 3, making a bend, flexure, or corrugation in the plate, and pierced by minute pin-holes 4 4.

I claim—

The design for a top plate for hydrocarbon- 25 burners, substantially as herein shown and described.

In testimony whereof I have affixed my signature in presence of two witnesses.

JOHN C. SPEIRS.

Witnesses:

M. B. MAY,
R. M. PIERSON.
